(57) **CLAIM**

The ornamental design for a portion of a display panel with an animated computer icon, substantially as shown and described.

DESCRIPTION

FIG. 1 is a front view of a first image in the sequence for a portion of a display panel with an animated computer icon, showing a first embodiment.

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a first image in the sequence for a portion of a display panel with an animated computer icon, showing a second embodiment thereof;

FIG. 10 is a front view of a second image thereof;

FIG. 11 is a front view of a third image thereof;

FIG. 12 is a front view of a fourth image thereof;

FIG. 13 is a front view of a fifth image thereof;

FIG. 14 is a front view of a sixth image thereof;

FIG. 15 is a front view of a seventh image thereof; and,

FIG. 16 is a front view of an eighth image thereof.

The appearance of the transitional image sequentially transitions between the images shown in FIGS. 1-8 and FIGS. 9-16. This process or period forms no part of the claimed design. The broken line bordering three sides of each figure illustrates edges of the display panel portion and forms no part of the claimed design. The broken lines within each figure illustrate graphical environmental features that form no part of the claimed design.
